Patented Nov. 19, 1974

233,703

HAND HELD ELECTRIC MASSAGER

Samuel L. McNair, Overland Park, Kans., assignor to
Dazey Products Co.

Filed Dec. 15, 1972, Ser. No. 315,629

Term of patent 14 years

Int. Cl. D24—04, 99

U.S. Cl. D83—1 T

Fig. 1.

Fig. 2.

Fig. 3.

Fig. 4.

Fig. 5.

FIG. 1 is a perspective view of a hand held electric massager showing my new design;

FIG. 2 is an end elevational view, on an enlarged scale, of same, the other end being substantially the same in appearance;

FIG. 3 is a side elevational view of same, taken from the opposite side as seen in FIG. 1, the two sides being substantially the same in appearance;

FIG. 4 is a top plan view of same; and

FIG. 5 is a bottom plan view of same.

I claim:

The ornamental design for a hand held electric massager, as shown and described.
